(57) **CLAIM**

The ornamental design for a beverage bottle handle, as shown and described.

DESCRIPTION

FIG. 1 is a top plan view of a beverage bottle handle showing the new design;

FIG. 2 is a side elevational view thereof;

FIG. 3 is an end elevational view thereof;

FIG. 4 is a right side elevational view of a bottle and bottle handle thereof;

FIG. 5 is a right side elevational view of a bottle and bottle handle thereof in a second position;

FIG. 6 is a front elevational view of a bottle and bottle handle thereof;

FIG. 7 is a front elevational view of a bottle and bottle handle thereof in a second position;

FIG. 8 is a rear elevational view of a bottle and bottle handle thereof; and,

FIG. 9 is a rear elevational view of a bottle and bottle handle thereof in a second position.

The broken line showing of a bottle is included for the purpose of depicting environment only and forms no part of the claimed design.
